UNITED STATES PATENT OFFICE

2,485,419

WASTEBASKET BALER

Roy S. Thompson, Westlake, Ohio

Application February 22, 1945, Serial No. 579,299

7 Claims. (Cl. 100—19)

1

The purpose of my invention has been to provide simple and convenient means for use in homes, offices, or the like, for the purpose of temporarily storing and finally baling newspapers. However, my invention may be availed of for the baling of miscellaneous flat sheets of paper or any similar material such as cloth sheets or articles in sheet form and made from plastic or equivalent substances.

A further object of my invention has been to utilize means of the character above referred to, in the form of a wastebasket or ordinary container, and which container is equipped with devices for engaging twine or string members held in position on the container so as to receive therebetween the newspapers or like articles which are to be tied or bound up, so that when the container or basket is full and ready for the final baling operation, the said string or twine members may be readily tied in a convenient manner so as to embrace the package of papers to be baled and thereafter tied, so as to secure the said papers or equivalent articles in a bundle convenient for handling purposes.

Still another object of my invention has been to produce a convenient baling basket or container which is largely of conventional form, preferably rectangular, and which is constructed with means for facilitating the baling operation of papers received or stored therein, along the lines above referred to.

Still another object of my invention has been to design the baling basket or container of the invention hereinafter described, so as to be of such simplified construction that it may be manufactured at relatively low cost, practically the same in fact as any ordinary rectangular metal container or wastebasket, or one of suitable material as useful as metal.

A full understanding of my invention may be had upon reference to the accompanying drawings, in which:

Figure 1 is a side elevation of a baling container or basket embodying my invention.

Figure 2 is an end view of the same.

Figure 3 is a top plan view of the same.

Figure 4 is a fragmentary sectional view taken about on the line 4—4 of Figure 1, showing more clearly the form of the detent or twine engaging member.

Figure 5 is a fragmentary sectional view taken about on the line 5—5 of Figure 1, showing more clearly the struck-out form of the anchoring lug for the ends of the twine or string members.

2

Specifically describing a preferred form of my invention in conjunction with the drawings in which similar reference characters refer to similar parts throughout, I refer first to Figures 1 to 3 inclusive.

It will be seen from the above figures of the drawings that my baling container or basket comprises a body of generally rectangular form composed of the sides 1, the ends 2, and the bottom 3. It is immaterial to my invention just how these parts of the body are constructed to assemble the same. The body, in fact, may be made in any conventional or known manner, as for instance by forming the sides with the bottom in an integral manner, and attaching thereto the ends 2.

Referring particularly to Figure 2, I note that the end 2 of the container or receptacle as constructed is formed with a struck-out projection 20 of somewhat triangular form constituting an anchor lug 4. It is contemplated that the end of a string member may be interlocked with this anchor lug 4 by engagement as shown in Figure 2. As will be seen later, the anchor lug 4 will have 25 an additional function of being a cutting member for the twine or string member interengaged therewith under some conditions. The lug 4 is struck outwardly from the plane of the end 2 as shown in Figure 2, and near to said lug 4 but 30 a little closer to the receptacle bottom is located a detent or twine engaging member 5. The member 5 is of somewhat peculiar construction. It is, generally speaking, of somewhat rectangular form, and is provided in the end 2 of the receptacle by cutting from the latter a clearance space designated 6 which is somewhat of C-form. Specifically speaking, the detent or twine engaging member 5 is peculiarly formed in that the central portion thereof between the upper and lower edges is pressed inwardly to provide a concave cross section, as seen best in Figure 4. Also, the upper edges of the said lug or member 5 are curved slightly in a direction opposite to the concave curve or contour of the central portion of the lug. The purpose of this construction will appear more fully hereinafter.

Now then, referring further to the general construction of my baling container, I note that on each end of the container there is provided one 50 of the anchor lugs 4 and one of the detent or twine engaging lugs 5. Again, on each side of the container I provide two sets of the lugs or members 4 and 5, each set substantially identical with that which has been described in conjunction with the showing of Figure 2. As seen in 55

Figure 1, each pair of the lugs or members 4 and 5 on the side 1 illustrated, is located adjacent to the end 2 of the container or receptacle adjacent to which said pair of members is disposed.

By reason of the provision of the anchoring and detent members 4 and 5 which I have described as carried by the end and sides of the container or receptacle, I am enabled to secure in place upon the sides and ends of the container three twine or string members 7, so disposed on and in the receptacle as to be located beneath and at the sides of a pile of papers assembled in the receptacle, such as newspapers, flat sheets, or the like, and when the papers fill the receptacle the several string or twine members may be readily tied for bundling the papers securely together.

I now describe how the twine members are applied to the receptacle preliminary to the filling of the same with the papers above referred to.

As seen best in Figures 2 and 3, I take a piece of twine and engage one end thereof, the free end from a ball preferably, with the anchor lug 4 on one end 2 of the receptacle. I then train the twine upwardly over the top edge of said end 2 and downwardly along the inner side of said end 2 until I interengage the twine intermediate its ends with the detent member 5 on the said end 2 just referred to. The twine member 7 being described is engaged with the member 5 by simply carrying the twine into the clearance space 6 of the member 5 and looping it around the latter at its outer side. From thence the twine is carried along the bottom of the receptacle to the opposite end 2 of the latter, looped around the detent member 5 at said opposite end in the same manner as previously described, and then carried up the inner side or face of the opposite end 2 of the container over the top edge and down into engagement with the anchor lug 4 slightly protruding from the outer face of said opposite end 2. When in engagement with the anchor lug 4 last mentioned, by a slight jerk of the twine, the latter may be cut owing to its interengagement with the lower edge of the last mentioned anchor member or lug 4.

Thus we have the twine member, just described, interengaged with the outer side of one end of the receptacle or container, interengaged with the inner side of said end near the bottom 3, extending longitudinally across along the bottom to the opposite end, and interengaged with the latter near its bottom portion on its inner face, and carried on up over the upper edge of said opposite end 2, down into the final engagement with the anchor lug 4 carried by the last mentioned end 2.

Now I contemplate using in the construction of the baling container just described, two other twine members which are interengaged with anchor lugs at one end, which anchor lugs are on one side 1 of the receptacle. Then I carry these twine members over the said side of the receptacle at its upper edge and cause the twine members to be engaged in the manner I have previously described with regard to the ends 2 of the receptacle, but in this instance with the sides 1.

By the above arrangement I have located on the receptacle three separate twine or string members ready for tying operation. The string or twine members designated 7 in the drawings are so disposed that they will not interfere in any way with the emplacement in the container body of newspapers or flat sheets, and when the

container has been filled with such material, it is obvious that the person baling the material can tie same very quickly by merely disengaging the ends of the twine members from the lugs 4, and correspondingly disengaging the intermediate portions of the twine members from the detent lugs 5 by merely moving the end of a finger parallel with the bottom 3 of the receptacle to accomplish the latter action. In this way the various twine members are freed from their engagement with the sides and ends of the receptacle, and thereupon the end portions of the string members may be tied over the top of the bundle of papers accumulated in the receptacle, and the baling of the papers or similar material into bundle form is completed in this manner.

By forming the curved upper and lower portions of the detent members 5 in the manner illustrated, the twine or string members 7 will not be cut or weakened by the engagement of the same with the members 5 in the preliminary adjustment or application of the twine members to the sides and ends of the receptacle.

It will be obvious that according to the size of the receptacle, the number of the lugs 4 and detent members 5 may be increased in the manufacture of the containers of my invention, or decreased. In other words, for certain sizes of receptacles, it may be desirable to have three or four sets of these members 4 and 5 on each side of the receptacle, or one set alone. Likewise, it may be desirable, under some conditions to have two sets of the members 4 and 5 on each end of the receptacle rather than one as illustrated in Figure 2. Generally speaking, however, for the particular purpose of bundling folded newspapers, the construction which is illustrated in my drawings will be ample for all purposes of obtaining expeditious baling of the paper.

Just as a convenient means for holding a ball of twine, an end of the container may be provided with a twine or cord ball box 8 to receive a ball of twine designated 9.

Having thus described my invention, what I claim as new and desire to secure by Letters Patent of the United States is:

1. In baling or packaging apparatus, in combination, a container comprising a bottom, sides, and ends, string member engaging lugs on and at the outside of the sides and ends, and string member engaging members at the inner faces of the sides and ends, said lugs and members being integral with the sides and ends.

2. In baling or packaging apparatus, in combination, a container comprising a bottom, sides, and ends, string member engaging lugs on and at the outside of the sides and ends, and string member engaging members at the inner faces of the sides and ends, said lugs and members being struck out from the material of the sides and ends and therefore integral portions of the sides and ends.

3. Apparatus as claimed in claim 1, in which the lugs are formed with string severing edges.

4. In baling or packaging apparatus in combination, a container comprising a bottom, sides, and ends, instrumentalities on and outside the sides and ends to engage the ends of string members, and instrumentalities at the inside of the sides and ends to detachably engage string members intermediate their ends, the outside instrumentalities of the ends and sides being lugs to detachably engage the ends of string members and disposed near the bottom, and the inside instrumentalities being located near the bottom

and being lugs detachably engaging intermediate portions of string members.

5. Apparatus as claimed in claim 4, in which the last mentioned inside lugs are formed convex in a direction inwardly from the inner faces of the sides and ends, to facilitate disengagement of the intermediate portions of string members therefrom.

6. In baling apparatus, in combination, a container comprising a bottom and sides, string anchoring engaging members at the outside of the said sides to anchor ends of a tying string, string engaging detent members on the sides engageable by a portion of the string contacting the inside of the sides and located near the bottom of the container, the said sides having clearance portions therethrough enabling string to be pushed off the detent members from the exterior of the sides when a mass to be packaged in the container is to be tied on freeing string from the anchoring members.

7. Baling apparatus as claimed in claim 6, in

which the detent members are parallel generally with the container bottom.

ROY S. THOMPSON.
